BALL RUNWAY TOY

Harry Wagner, Brooklyn, N. Y.

Application October 5, 1946, Serial No. 701,452

3 Claims. (Cl. 46—43)

1

This invention relates to new and useful improvements in a toy.

More specifically the present invention proposes the construction of a toy characterized by having a runway along which a ball can be rolled, the runway curving upwardly and forwardly at its rear end and terminating in an abutment which causes the ball to drop to an inclined shelf thereby providing amusement.

A further object is to provide a toy as aforesaid in which the shelf inclines upwardly at its rear portion and is connected at its front end to a vertical wall.

Still another object is to provide means hingeing the vertical wall at the top whereby it may be assigned to different positions to vary the angle of inclination of the shelf, means being provided for holding the vertical wall in any adjusted position.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a side view of a toy constructed in accordance with the present invention.

Fig. 2 is a fragmentary side view of the other side of the toy.

Fig. 3 is a front view of Fig. 2.

Fig. 4 is a side view of the hinge pintle.

Fig. 5 is an end view of a hinge pintle locking plate.

The toy, according to this invention, is mounted on legs 10 and is substantially rectangular in shape. It has a runway 11 which has a portion 11^a extended rearwardly for a suitable distance on a horizontal plane and which continues into a rear portion 11^b curved gradually upwardly, the runway being closed at the front end 12. The upper end of the rear portion 11^b of the runway continues into a forwardly extended top portion 11^c which overhangs the lower part of the rear upwardly curved portion 11^b. Along the sides of the runway 11 there are side walls 13. The upwardly curved portion 11^b and the top portion 11^c of the runway 11 are supported by a frame 14 which extends upward from the rear ends of the side walls 13. The runway is adapted to have balls 15, one being shown in Fig. 1, rolled along it.

A vertical wall 18 is connected to the frame 14 at the free end of the forwardly extended top

2

portion of the runway 11 by a hinged connection, the top of the wall 18 and the adjacent portion of the frame 14 having interfitting lugs 31 and 32 respectively, orificed to receive a hinge pin 33, best shown in Fig. 4. The lugs 31 are secured to the pin for rotation therewith by transverse pins 34. Thus the pin 33 rotates relative to the lugs 32. The transverse pins 34 fit in slots 35 in the hinge pin 33, permitting longitudinal movements of the hinge pin in the lugs 31—32 while preventing rotation of the hinge pin relative to the lugs 31 and thus to the vertical wall.

At one end the hinge pin has a disc shaped handle 36 from which extend a circular row of studs 37 adapted to fit in holes 38 formed in a disc 39 secured to the frame 14 by screws disposed in holes 40 in the disc 39, the disc 39 having a central orifice 41 through which the hinge pin 33 passes.

The bottom edge of the wall 18 is provided with a rearwardly upwardly inclined shelf 20 upon which the balls 15 are to fall after being rolled upon the runway 11.

The balls are rolled up the runway 11 to strike the wall 18 and fall upon the shelf 20 but the difficulty in playing with the toy may be varied by varying the angular position of the wall 18 so as to vary the angle of inclination of the shelf 20. For example, when it is desired to increase this angle from the position shown in Fig. 1, the handle 36 is pulled axially outwardly, freeing the studs 37 from the holes 38. The handle is then turned, swinging the wall 18 and the shelf 20. When the shelf 20 reaches the desired position, the handle 36 is pushed axially in a direction to push the studs 37 into the holes 38, locking the wall 18 in its new position.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a toy having a runway along which balls are adapted to be rolled and comprising a lower horizontal portion, a rear upwardly curved portion and a forwardly extended top portion overhanging the lower part of the rear upwardly curved portion, a frame supporting the rear part of said rear upwardly curved portion and said top portion, a vertical wall depending from said

frame at the free end of the forwardly extended top portion, a shelf attached to the bottom of said vertical wall and extended rearward beneath the forwardly extended top portion of the runway for receiving the balls after they have rolled the length of the runway, said vertical wall and said frame being formed with interfitting lugs defining a horizontal axis extended transversely of the runway, a hinge pin extended through said interfitting lugs and having a non-rotatable connection with the lugs of said vertical wall, and means for holding the hinge pin in various rotative positions relative to said lugs of said frame for holding said vertical wall and said shelf attached thereto in various angular positions relative to said frame.

2. In a toy having a runway along which balls are adapted to be rolled and comprising a lower horizontal portion, a rear upwardly curved portion and a forwardly extended top portion overhanging the lower part of the rear upwardly curved portion, a frame supporting the rear part of said rear upwardly curved portion and said top portion, a vertical wall depending from said frame at the free end of the forwardly extended top portion, a shelf attached to the bottom of said vertical wall and extended rearward beneath the forwardly extended top portion of the runway for receiving the balls after they have rolled the length of the runway, said vertical wall and said frame being formed with interfitting lugs defining a horizontal axis extended transversely of the runway, a hinge pin extended through said interfitting lugs, means for holding the hinge pin in various rotative positions relative to said frame for holding said vertical wall and said shelf attached thereto in various angular positions relative to said frame, and pins engaged through the lugs of said vertical wall and said hinge pin non-rotatively connecting said vertical wall to said hinge pin.

3. In a toy having a runway along which balls are adapted to be rolled and comprising a lower horizontal portion, a rear upwardly curved portion and a forwardly extended top portion overhanging the lower part of the rear upwardly

curved portion, a frame supporting the rear part of said rear upwardly curved portion and said top portion, a vertical wall depending from said frame at the free end of the forwardly extended top portion, a shelf attached to the bottom of said vertical wall and extended rearward beneath the forwardly extended top portion of the runway for receiving the balls after they have rolled the length of the runway, said vertical wall and said frame being formed with interfitting lugs defining a horizontal axis extended transversely of the runway, a hinge pin extended through said interfitting lugs, said hinge pin having a longitudinally slidable but non-rotative connection with the lugs of said vertical wall, and means for holding the hinge pin in various rotative positions relative to said lugs of said frame for holding said vertical wall and said shelf attached thereto in various angular positions relative to said frame, said holding means comprising a disc mounted on an extended end of said hinge pin, a disc mounted on the side of said frame concentric with the hinge pin and formed with a plurality of holes arranged concentrically about said hinge pin, and a plurality of complementary pins mounted on said first disc concentrically about said hinge pin and engaging the holes of said second disc for holding said hinge pin and said vertical wall against rotation, whereby said first disc may be manually moved in a direction to slide said hinge pin longitudinally, spacing said discs to disengage said complementary pins from said holes, and freeing said first disc and hinge pin to be rotated to adjust the angular position of said vertical wall and said shelf relative to said frame.

HARRY WAGNER.
